UNITED STATES PATENT OFFICE

ARTHUR P. PAINE, OF NEW YORK, N. Y., ASSIGNOR TO MERGENTHALER LINOTYPE COMPANY, A CORPORATION OF NEW YORK

SLUG CASTING MOLD

Application filed February 3, 1930. Serial No. 425,361.

This invention relates to slug casting machines, such as linotype machines of the general organization represented in U. S. Letters Patent to O. Mergenthaler, No. 436,532, wherein a melting pot is arranged to deliver molten metal into a slotted mold and up against a composed line of matrices to produce a type bar or slug bearing on its edge type characters corresponding to the intaglio characters of the matrices. As these molds are usually constructed, the side walls of the mold slot or cavity are formed by a bottom or body portion and an upper or cap portion, while the end walls are formed by two end portions or liners held in place between the body and cap portions. Ordinarily, the molds are made to produce slugs not exceeding 30 ems in length, but for certain classes of work, such as advertising or book work, the molds are made to produce slugs running as high as 42 ems in length and 45 pt. or more in thickness.

In the production of slugs above 12 pt. thickness, whether they be cast in the regular molds of standard height or in low "furniture" molds, it is desirable that they be light in weight yet of strong and durable construction. It is the practice, therefore, to cast such slugs in skeleton form, the regular mold being usually provided with a series of core sections integral with the mold cap to produce cavities in one of the side faces of the cast slug, and the furniture mold (whose side faces should be smooth and unbroken for reasons well-known to the art) being usually provided with a single core member centrally positioned within the mold cavity and extending throughout the length thereof to produce a corresponding cavity within the body of the slug or between its solid side faces. In the commercial furniture molds, the core member is ordinarily supported at its opposite ends by the liners of which it is or may be an integral part and, like other adjacent portions of the mold, is made of hardened steel. It is thus necessary to observe certain precautions in the design of the core member in order that it may be capable of resisting the warping tendencies to which it is subject when the mold is in use. In other words, the size

and form of the core's cross section is largely determined by its length and, as ordinarily constructed, its width is but slightly less than the height of the mold.

While the commercial furniture molds are capable of producing slugs ranging in thickness above a minimum of 24 pt., the core member for slugs of less thickness would have to be much too thin to maintain its original shape under ordinary casting conditions, particularly if the mold were more than 30 ems in length. Furthermore, due to the width of the core member, the casting surfaces thereof offer considerable resistance to the ejection of the slugs and, in slugs of the maximum thickness, are likely to cause damage to the ejector blades or a jamming of the mechanism.

The present invention is intended to obviate the above and other objections, and contemplates a furniture mold construction wherein the core member may be of any suitable size or cross-section irrespective of the size of the mold or of the warping tendencies of the metal of the core. To this end, it is proposed specifically to support the core member at the back of the mold by the cap and body portions at various selected points throughout its length, instead of at its opposite ends or by the mold liners only, so that all strains or stresses due to the expansion and contraction of the core during the slug casting periods may be transmitted directly to the mold at the points of support. As thus supported, the core member may be made with relatively narrow casting surfaces to facilitate the ejection of the slugs; and, if desired, may be made thinner than heretofore so as to serve in casting slugs below 24 pt. in thickness.

In the preferred embodiment illustrated, the core member is shown in such narrow form, and would or might therefore be insufficient in itself to reduce the weight of the slug to the extent required. For this reason, it is further proposed in carrying out the invention to make use of a second core member to fill the mold cavity partly at the front. This second core member is formed on a quad block or blank matrix bar and com-

prises a series of sections which are adapted to enter the mold cavity as the mold is carried forward to the casting position against the quad block, and which are adapted to be disengaged from the slug immediately after the cast, as the mold is retracted.

The exact relation of the parts and the precise manner of supporting the core members will best be understood from the detailed description to follow.

In the accompanying drawings, the invention has been shown merely in preferred form and by way of example and as applied to a particular type of mold, but obviously many changes and variations may be made therein and in its mode of application which will still be comprised within its spirit. It should, therefore, be understood that the invention is not limited to any specific form or embodiment except insofar as such limitations are specified in the claims.

Referring to the drawings:

Fig. 1 is a perspective view of a mold, partially disassembled, equipped with the present improvements;

Fig. 2 is a perspective view of the rear core member detached;

Fig. 3 is a vertical section through the mold and parts associated therewith;

Fig. 4 is a horizontal section taken on the line 4—4 of Fig. 3; and

Fig. 5 is a perspective view of a slug cast in the improved mold.

While the invention has been herein illustrated as applied to a 42 em mold of the composite type disclosed in the patent to R. R. Mead, No. 1,568,386, it is equally applicable to the standard unrecessed molds and to unrecessed molds of other types.

Generally, the mold proper (here shown as of the "furniture" type) comprises the body A, the cap B, and the intermediate liners C, D, these parts being held together in assembled relation by posts E rising from the body A and engaging in notches formed in the opposite ends of the cap B. The mold body A (see Figs. 1 and 3) is made up of an inner hardened steel base portion A¹, constituting the lower side wall of the mold cavity, and an outer unhardened steel reinforcing portion A², the two portions having a machined fit and being held together by clamping screws A³. Likewise, the mold cap B is made up of an inner hardened steel base portion B¹, constituting the upper side wall of the mold cavity, and an outer unhardened steel reinforcing portion B², the two sections also having a machined fit and held together by clamping screws B³.

The mold, as usual, is mounted in a rotatable wheel or disk F which, prior to the casting operation, is moved forward to carry the mold against a matrix line or quad block K while clamped between vise jaws F¹ and supported in the first elevator G (see broken

lines, Fig. 3). The mold cavity is thus closed at the front by the matrix line or quad block and immediately thereafter is sealed at the rear by the mouthpiece of the metal pot H, which is advanced against the back of the mold preparatory to the descent of the pot plungers and the casting of the slug. After the cast, the mold disk is retracted to break its engagement with the matrix line or quad block and then rotated to carry the mold to the slug ejecting position, all as is well understood in the art.

The core member J of the improved furniture mold (Fig. 3) is centrally positioned as usual transversely of the mold cavity with its rear edge flush with the back of the mold, and the top and bottom faces thereof converge toward the front so as to facilitate their disengagement from the slug at the time of ejection. In the present instance, however, the core member J is supported by both the cap and body portions of the mold, being provided at selected points along its rear edge with three upper supporting arms J¹ secured by counter-sunk screws j to the base portion B¹ of the cap, and with three lower supporting arms J² vertically aligned with the respective arms J¹ and secured by similar screws j¹ to the base portion A¹ of the mold body. While a greater number of supporting arms might be employed, the three sets shown have been found in practice to be quite satisfactory.

The upper arms J¹ are mounted in transverse cuts or recesses b formed in the base portion B¹ of the cap B, and the lower arms J² are similarly mounted in corresponding recesses a formed in the base portion A¹ of the body A, so that the arms will be rigidly supported in a lateral direction and a smooth even surface presented to the mouthpiece F¹ of the metal pot. In this connection, it may be noted (see Figs. 1 and 3) that the free ends of the arms J¹, J² are flush with the outer side faces of the base portions A¹, B¹, respectively, and abut squarely against the underfaces of the reinforcing portions A², B². Consequently, any vertical strains or stresses set up in the core member will be transmitted directly to the said reinforcing portions of the mold instead of to the screws j, j¹. As a matter of fact, the screws merely serve to maintain the core member in place against the back of the mold, all other strains or stresses (which are mainly in a forward direction) being fully borne or absorbed by the base portions A¹ and B¹.

The core member J, in the present embodiment, is of exactly the same length as that of the mold cavity, and the supporting arms J¹, J² thereof are arranged, one pair at each extreme end of the core, and the third pair about midway of its length. The ends of the core member, it will be observed (see Figs. 1 and 4), fit closely against the inner or cast-

ing faces of the liners C, D, and these faces are made perfectly square instead of being formed with the usual rib or lip at their rear edges.

5 The particular form and relation of the parts just described, while not absolutely essential, are desirable for the reason that the slug M (Fig. 5) cast in the mold will be formed at its opposite ends with transverse notches m , which are produced therein by the corresponding pairs of arms J^1 , J^2 . These notches m serve in place of the customary notches produced in the slugs by the liner ribs without destroying the general symmetry of the slug. Moreover, the presence of the core 10 supporting arms does not prevent the use of the sectional ejector blade employed in the commercial linotype machine, since the location of the arms is such as merely to necessitate the removal of three sections of said 15 blade, namely, the uppermost and lowermost sections to clear the end supporting arms J^2 , and the middle section to clear the intermediate supporting arm J^1 .

20 25 It is to be noted (see Figs. 3 and 4) that the core member J extends forwardly from the back of the mold slightly less than half-way through the mold cavity. The longitudinal recess m^1 formed thereby in the base 30 of the slug M might therefore, as previously stated, be insufficient in itself to reduce the weight of the slug to the extent desired. Hence, the quad block K is provided with a series of core sections K^1 and a corresponding 35 series of intervening notches K^2 , the core sections K^1 being adapted to produce recesses m^2 in the top face of the slug M, and the notches K^2 transverse ribs m^3 located between said slug recesses.

40 The core sections K^1 are made preferably of the same width as that of the core member J, so that when the mold is in casting position against the quad block K they will extend into the mold cavity a like distance from 45 the front with their rear faces in predetermined spaced relation to the front face of the core J. There is thus produced in the slug M, between the recesses m^1 and m^2 , a horizontal rib m^4 which extends throughout 50 the length of the slug (see Fig. 5). This rib m^4 together with the transverse ribs m^3 give the slug great rigidity and enable it easily to withstand the lateral pressure to which it is subjected when clamped in the printing 55 form. The upper and lower faces of the core sections K^1 (Fig. 3), as well as the end faces thereof (Fig. 4), converges rearwardly in order to facilitate their disengagement from the slug as the mold disk F is backed away 60 from the quad block preparatory to the rotation of the disk to the slug ejecting position. The core sections K^1 , being supported free and clear of the mold at the time of the ejection of the slug, in no way interfere with 65 that operation.

If desired, the front core sections K^2 could be extended sufficiently to make contact with the rear core member J, but by leaving a continuous uninterrupted space between the cores, the slug is cast with the central horizontal rib m^4 , which is desirable, and moreover the molten metal may be forced into the mold from a single series of discharge orifices (as shown in Fig. 3) and still flow around the core sections and fill the mold cavity completely without difficulty.

70 Other advantages flowing from the improved mold might be mentioned, but enough has been said to indicate the advance made in the art.

80 Having thus described my invention, what I claim is:

1. In or for a slug casting machine, a mold comprising side and end walls defining between them a mold cavity, and a single core member extending substantially throughout the length of the mold cavity, said member being supported at the back of the mold by both side walls and independently of the end walls.

85 2. In or for a slug casting machine, a mold comprising side and end walls defining between them a mold cavity, and a single core member extending substantially throughout the length of the mold cavity, said member being supported at the back of the mold by one of the side walls and independently of the end walls.

90 3. In or for a slug casting machine, a mold comprising side and end walls defining between them a mold cavity, and a single core member extending substantially throughout the length of the mold cavity, said member being positioned between the side walls in spaced relation thereto and supported by the mold at the back independently of the end walls.

100 4. In or for a slug casting machine, a mold comprising side and end walls defining between them a mold cavity, and a single core member extending substantially throughout the length of the mold cavity, said member being supported at and between its ends at the back of the mold by both side walls and independently of the end walls.

110 5. In or for a slug casting machine, a mold comprising cap and body portions, intermediate liners or end walls, and a core member supported at the back of the mold solely by both the cap and body portions.

115 6. In or for a slug casting machine, a mold comprising side and end walls defining between them a mold cavity, and a core member positioned between the side walls in spaced relation thereto, said member being supported at its opposite ends and at points therebetween solely by both side walls of the mold walls.

120 7. In or for a slug casting machine, a mold comprising side and end walls defining be-

- tween them a mold cavity, and a single core member positioned between the side walls in spaced relation thereto and extending substantially throughout the length of the mold cavity, said core member being provided with a plurality of lateral arms spaced apart and secured at the back of the mold to the side walls.
8. In or for a slug casting machine, a composite mold comprising end walls, relatively thin side walls, reinforcing members applied to the side walls, and a core member supported at the back of the mold by both side walls to the exclusion of the end walls.
15. 9. In or for a slug casting machine, a composite mold comprising end walls, relatively thin side walls, reinforcing members applied to the side walls, and a core member provided with lateral supporting arms mounted in transverse notches cut through the rear edges of said side walls, for the purpose described.
10. In a slug casting machine, the combination with a mold comprising cap and body portions, intermediate liners or end walls, and a core member supported at the back of the mold by both the cap and body portions, said core member extending a given distance within the mold cavity, of a quad block formed with a core section extending from the front of the mold within said cavity but having its rear face terminating short of the front face of the rear core member, for the purpose described.
35. 11. In a slug casting machine, the combination with a mold comprising cap and body portions, intermediate liners or end walls, and a core member supported at the back of the mold by both the cap and body portions, said core member extending a given distance within the mold cavity, of a quad block formed with a plurality of core sections separated from each other by intermediate recesses and extending from the front of the mold within said cavity but having their rear faces terminating short of the front face of the rear core member.
50. 12. In or for a slug casting machine, a mold comprising side and end walls defining between them a mold cavity, a core member extending substantially throughout the length of the mold cavity and supported at the rear of said cavity, and a second core member also extending substantially throughout the length of the mold cavity and supported at the front of said cavity, the two core members being separated from each other to leave a continuous uninterrupted space between them.
55. 60. 13. A mold according to claim 12 wherein the front core member is made up of a plurality of sections separated from each other by fore-and-aft recesses.
65. 14. In or for a slug casting mold, a core member formed at its opposite ends and on

its opposite edges with integral arms adapted for attachment to the side walls of the mold.

15. In or for a slug casting mold, a core member formed at its opposite ends and about midway of its length and on its opposite edges with integral arms adapted for attachment to the side walls of the mold.

In testimony whereof, this specification has been duly signed by

ARTHUR P. PAINE.
